UNITED STATES PATENT OFFICE

141,512

DESIGN FOR A COMBINATION CHAIR AND TELEPHONE STAND

John Joseph Schmedinghoff, Kansas City, Mo.

Application March 10, 1945, Serial No. 118,404

Term of patent 14 years

(Cl. D33—14)

To all whom it may concern:

Be it known that I, John Joseph Schmedinghoff, a citizen of the United States, residing at Kansas City, in the county of Jackson and State of Missouri, have invented a new, original, and ornamental Design for a Combination Chair and Telephone Stand, of which the following is a specification, reference being had to the accompanying drawing, forming a part thereof.

Fig. 1 is a top plan view of the combination chair and telephone stand, showing my new design.

Fig. 2 is a side elevational view thereof.

Fig. 3 is an end elevational view thereof; and

Fig. 4 is a perspective view of the combination chair and telephone stand.

I claim:

The ornamental design for a combination chair and telephone stand, as shown.

JOHN JOSEPH SCHMEDINGHOFF.
